(57) **CLAIM**

The ornamental design for a base for container, as shown and described.

DESCRIPTION

FIG. 1 is a front perspective view of a base for container showing our new design;

FIG. 2 is a rear perspective view thereof;

FIG. 3 is a bottom perspective view thereof;

FIG. 4 is a front view thereof;

FIG. 5 is a rear view thereof;

FIG. 6 is a top view thereof;

FIG. 7 is a bottom view thereof;

FIG. 8 is a left side view thereof; and,

FIG. 9 is a right side view thereof.

The broken lines in the drawing depict portions of the base for container that form no part of the claimed design.
